UNITED STATES PATENT OFFICE.

RICHARD M. HOLLINGSHEAD, OF CAMDEN, NEW JERSEY.

DESIGN FOR A BOX-LID.

SPECIFICATION forming part of Design No. 30,161, dated February 7, 1899.

Application filed January 16, 1899. Serial No. 702,362. Term of patent 3½ years.

To all whom it may concern:

Be it known that I, RICHARD M. HOLLINGSHEAD, a citizen of the United States, residing at Camden, in the county of Camden and State of New Jersey, have invented and produced a new and useful Design for a Box-Lid, of which the following is a specification, reference being had to the accompanying drawing, which fully illustrates my design.

10 Adjacent to the rim or circumference A are the concentric circles B B', between which are the short radial lines C, followed by the radial spear-heads D, and the concentric cir-

cles E E', inclosing the ornamental arcs F F. The field or ground G has centrally disposed 15 the oblong figure H, surmounted by the semi-elliptical ornament or top I.

I claim—

The design for a box-lid herein shown and described.

In testimony whereof I affix my signature in presence of two witnesses.

RICHARD M. HOLLINGSHEAD.

Witnesses:

FRANCIS D. PASTORIUS,
B. D. ARCHER.
